UNITED STATES PATENT OFFICE.

IRVING L. KLEINFIELD, OF BROOKLYN, NEW YORK.

DESIGN FOR AN ELECTRIC-LAMP STAND.

Application filed June 12, 1922. Serial No. 2,640. Term of patent 3½ years.

To all whom it may concern:

Be it known that I, IRVING L. KLEINFIELD, a citizen of the United States, residing in the borough of Brooklyn, county of Kings, city and State of New York, have invented a new, original, and ornamental Design for Electric-Lamp Stands, of which the following is a specification, reference being had to the accompanying drawings, forming part thereof.

Fig. 1, is a top or plan view;

Fig. 2, is a side elevation; and Fig. 3, a section taken upon plane of line 3—3 Fig. 2, of an electric lamp stand, showing my new design.

I claim:

The ornamental design for an electric lamp stand, as shown.

IRVING L. KLEINFIELD.
